UNITED STATES PATENT OFFICE.

FREDERICK D. COOK, OF BLAIRSVILLE, PENNSYLVANIA.

HEATING STOVE OR FURNACE.

1,360,181.

Specification of Letters Patent. Patented Nov. 23, 1920.

Application filed August 22, 1919. Serial No. 319,143.

To all whom it may concern:

Be it known that I, FREDERICK D. Cook, a citizen of the United States, and a resident of Blairstown, in the county of Indiana and State of Pennsylvania, have invented a new and Improved Heating Stove or Furnace, of which the following is a description.

Stoves and furnaces particularly house 10 stoves and furnaces are made ordinarily of cast or of sheet metal. The cast metal is more rigid and holds its shape when brought to a red heat but it is more porous than sheet metal, thus not so efficient in transmitting 15 the heat, and the fire pot is liable to crack when unevenly heated. To overcome the tendency to crack, the fire pots are made either heavy or ribbed or they are lined with fire brick at the fire zone and these features 20 when employed diminish heat radiation. Sheet metal on the other hand is more flexible than the cast metal and this quality is rapidly increased as the material is brought to a red heat for which reason it is necessary 25 when sheet metal is used for the fire pot to line the sheet metal at the fire pot with fire brick. The fire brick diminishes radiation and also, if the firing is such as to produce a 30 high heat there is danger of the shell buckling or bulging just above the fire line. Sheet metal has an advantage that it may be used much thinner than cast metal and for 35 this reason together with its greater density it is much more efficient in transmitting heat.

The prime object of my invention is to so combine the sheet metal and cast metal as to overcome or minimize the defects of these 40 metals as used in the usual ways and produce a stove possessing the meritorious attributes of both metals.

The stated object is attained in the novel construction and arrangement of parts hereinafter particularly described and claimed.

Reference is to be had to the accompanying drawings forming a part of this specification, it being understood that the drawings are merely illustrative of one example 45 of the invention.

Figure 1 is a partly sectional side elevation of a heater constructed in accordance 50 with my invention;

Fig. 2 is a sectional plan view on the line 2—2, Fig. 1;

Fig. 3 is a perspective view of the fire pot 55 in its preferred form.

In carrying out my invention in accordance with the illustrated example a cast metal base 10 is provided of any suitable shape having an ash door 11 and any approved form of grate and appurtenances, a grate, 12, being here conventionally shown. Upon the top of cast base 10 I provide a cast metal fire pot 13 made in one piece and advantageously a separate casting from the 60 base. The upper portion of the body of the stove or heater constituting the radiating chamber thereof is made in the form of a sheet metal shell 14 which has a closed top 65 15 of any approved construction and an open lower end, said shell being provided with a fire door 16 as well as an opening for receiving a stove pipe 17. The shell 14 is passed downward over the fire pot 13 and extends about the same with a snug fit. The 70 lower edge of the shell 14 is supported on the base 10, the shell extending preferably at the inside of an upwardly projecting annular flange 18 of said base to which the shell is fastened by suitable rivets or bolts 75 80 indicated at 19.

With the described construction the sheet metal shell fitting snugly about the cast metal fire pot forms for the latter a jacket which by minimizing the possibility of the 85 fire pot cooling in spots materially lessens or entirely eliminates the danger of the fire pot cracking and even should it crack the jacket will effectively prevent leakage of any smoke or gases from the fire. At the 90 same time the shell is protected against buckling tendencies, radiation is in no way interfered with as when fire brick lining is used, radiation being in fact promoted by my arrangement, and also, a much thinner 95 cast metal fire box can be used because closely jacketed with the sheet metal.

The fire pot 13, it will be observed, is given a shape to be somewhat higher on that side opposite the fire door or charging door 100 16, the purpose being to guard against the piling of fuel over the top of the fire pot against the thin shell 14, the tendency in firing being to pile the charge somewhat higher at the far side from the fire door.

I would state in conclusion that while the illustrated example constitutes a practical embodiment of my invention, I do not limit

myself strictly to the mechanical details herein illustrated, since manifestly the same can be considerably varied without departure from the spirit of the invention as defined in the appended claims.

Having thus described my invention, I claim:

1. A stove or heater of the class described, including a cast metal base, a cast metal fire pot thereon, and a sheet metal shell forming the upper portion of the structure, said shell being open at its lower end and fitting snugly about said fire pot.
- 10 2. A stove or heater of the class described including a cast metal base, a separate cast metal fire pot above and resting on said base, and a sheet metal shell forming the upper portion of the structure, said shell being open at its lower end and fitting snugly about said fire pot, the lower end of the shell being fastened to said base.
- 15 3. A stove or heater of the class described including a cast metal base, a grate thereon, a separate cast metal fire pot above and rest-

ing on said base outward of the grate, said base having an upstanding flange outside of the lower end of said fire pot, and a sheet metal shell forming the upper portion of the structure, said shell being open at its lower end and fitting snugly about said fire pot between the same and said flange and being fastened to said flange.

4. A stove or heater including a cast metal fire pot, and a sheet metal shell forming the upper portion of the structure, said shell being open at its lower end and fitting as a jacket snugly about said fire pot.

5. A stove or heater of the class described, including a base, a cast metal fire pot thereon, and a sheet metal shell extending about said cast metal fire pot and closely fitting the same, to prevent unequal heating and cooling of said cast metal fire pot.

6. A stove, including a cast metal fire pot, and a sheet metal shell extending about said cast metal fire pot and closely fitting the same.

FREDERICK D. COOK.
